CLAIM

(57) The ornamental design for a wireless remote control, as shown and described.

DESCRIPTION

FIG. 1 is a perspective view of a wireless remote control according to our invention;

FIG. 2 is a left side view of the second embodiment thereof;

FIG. 3 is a right side view thereof;

FIG. 4 is a back side view thereof;

FIG. 5 is a front side view thereof;

FIG. 6 is a top plan view thereof; and,

FIG. 7 is a bottom plan view thereof.
